UNITED STATES PATENT OFFICE.

FRANK A. THELEN, OF KEWANEE, ILLINOIS, ASSIGNOR TO ADOLPH MOHLER, OF KEWANEE, ILLINOIS.

BOTTLE-CAPPING DEVICE.

1,065,638.

Specification of Letters Patent. Patented June 24, 1913.

Application filed November 16, 1910. Serial No. 592,716.

To all whom it may concern:

Be it known that I, FRANK A. THELEN, a citizen of the United States, and a resident of the city of Kewanee, county of 5 Henry, and State of Illinois, have invented certain new and useful Improvements in Bottle-Capping Devices, of which the following is a specification.

My invention relates to improvements in 10 devices for applying caps or crowns to bottles.

The object of my invention is the production of a device of the character mentioned by means of which bottles may be readily 15 and expeditiously capped or crowned and without the need of employment of skilled labor.

A further object is the provision of a bottle capping device which will be of durable 20 and economical construction and efficient in operation.

Other objects will appear hereinafter.

With these objects in view my invention 25 consists in the combinations and arrangement of parts hereinafter described and claimed.

My invention will be best understood by reference to the accompanying drawing forming a part of this specification and in 30 which,

Figure 1 is a front elevation of a bottle capping device embodying my invention, a portion of the operating lever being broken off and shown in section, Fig. 2 is a sectional 35 side elevation of the device arranged for applying a cap to a bottle, a bottle being shown in dotted lines, and Fig. 3 is a sectional detail of the base and bottle supporting blocks of the device.

40 The preferred form of my invention as illustrated in the drawing comprises a flat, preferably metallic base 1 substantially circular in outline. Rising from said base is a standard 2, the lower end of the latter being rigidly secured to said base by means of 45 screws 3 and nuts 4. The upper end of the standard 2 is bifurcated as at 5 for the reception of the inner ends of a lever 6 and a link 7 which are pivotally secured thereto by 50 means of pivotal pins 8. The lever 6, as will be observed, is of considerable length, the outer extremity thereof terminating in a handle or grip 9. Said lever 6 and link 7 are arranged in parallelism, the same being 55 pivotally secured as at 10 with the bifur-

cated upper end portion of a cap applying plunger 11; the arrangement being such, as will be observed, that irrespective of the angular positions of said lever and link, said plunger will always be carried in a vertical 60 position. The lower end portion 12 of the plunger 11 is enlarged as noted, the same being provided with a circular recess 13 which is open at its lower end. The lower end portion of the recess 13 is of a diameter 65 slightly greater than that of the upper end portion thereof, resulting in the formation of an annular shoulder 14 which is preferably round as clearly shown in Fig. 2. Arranged within the upper end portion of the 70 recess 13 is a helical compression spring 15 the upper end of said spring being secured to the head 12 of the plunger, the lower extremity thereof being free. Arranged upon the lower edge of the head 12 is a 75 concentric resilient, preferably rubber ring or retainer 16, the latter being secured in position by means of a metallic ring or flange 17 secured to said head 12 by means of screws 18. The opening in the retainer 80 16 is of a diameter slightly less than that of the lower end portion of recess 13, the opening in the ring 17 being of a diameter coincident with that of said end of said recess 13.

85 Arranged upon the base 1 directly below the plunger 11 is a block 19 upon which may be arranged the bottle to be operated upon. A rubber mat or cushion 20 is preferably interposed between the block 19 and said base in order to cushion the shock to which the bottle is subjected in the application of a cap thereto. In order to maintain the block 19 in proper position upon the base 1, the former is provided with a central 90 reduced extension 21 which engages an opening 22 provided for the reception thereof in said base. In order that the device will be adapted to accommodate bottles of various heights an additional section 23 may be arranged upon the block 19, such section being held central or coaxial upon the block 19 by means of a depending reduced extension 24 which engages a recess 25 provided for the reception thereof in the upper side of 100 105 said block 19.

110 The operation of the device is as follows: A cap or crown in uncrimped condition is first pushed upward through the ring 17, retainer 16 and the lower end of the recess 13,

said cap being held in position against accidentally dropping by means of the retainer 16 which will press against the sides thereof, the opening in said retainer as is understood 5 being of less diameter than that of the cap. The operating lever is then raised and the bottle placed in position upon the base of the device or the supporting blocks arranged thereon, after which the lever is forced down- 10 wardly so as to drive the plunger forcibly over the neck of the bottle. The downward movement of the plunger will carry the cap or crown directly over the mouth of the bottle, continued depression of said lever effecting the bending or crimping of the edges of 15 the cap firmly about the bead provided at the mouth of the bottle, this crimping or bending being effected by contact of the peripheral edge of the cap with the shoulder 20 14 in the manner as will be readily understood. After this operation the operating lever will again be raised out of engagement with the cap which will remain in position upon the mouth of the bottle. The spring 25 15 which is arranged in the upper end of the recess 13 of the plunger serves to hold the cap against the neck of the bottle before the crimping operation to insure the correct positioning of said cap before the same is 30 crimped upon or locked to the bottle.

It is apparent with a device of the construction as set forth that caps may be readily and quickly applied to bottles without the need of exercising a great deal of 35 care or skill. The device is of simple and economical construction and hence may be manufactured at a low cost; and the same is not susceptible to readily becoming inoperative.

40 While I have illustrated and described the

preferred construction for carrying my invention into effect this may be varied somewhat without departing from the spirit of the invention. I, therefore, do not wish to be limited to the exact details of construction as set forth but desire to avail myself of such variations and modifications as come within the scope of the appended claims. 45

Having described my invention what I deem as new and desire to secure by Letters 50 Patent is:

1. A bottle capping machine comprising a base, a standard, a capping plunger mounted on said standard and above said base, a supporting block for the bottle to be capped, a 55 depending central portion on said block, there being an aperture in said base to receive the same, and an annular cushion between said block and said base and surrounding said depending portion, substantially as described.

2. In a bottle capping machine, a base, a standard, a capping plunger mounted on said standard above said base, said base having an aperture, a supporting block provided 65 with a depending portion adapted to engage in said aperture and provided with a recess in its upper end similar to the aperture in the base, and a supplemental block, said supplemental block being provided with a depending lug adapted to engage in said recess, substantially as described.

In testimony whereof I have signed my name to this specification in the presence of two subscribing witnesses.

FRANK A. THELEN.
